UNITED STATES PATENT OFFICE.

RUSSELL V. JUDSON, OF DETROIT, MICHIGAN.

ADJUSTABLE SORTING MACHINE.

Application filed September 27, 1926. Serial No. 138,081.

This is a machine of the centrifugal type, operating on substantially the same principle as the machine shown in my Patent No. 1,366,665, granted Jan. 25, 1921, and the present machine includes, as some of its principal elements, several pairs of rolls of yielding material, arranged in radiating relation to a vertical axis of rotation, so that beans, seeds or other matter to be sorted, if fed on to the rolls near said axis, are carried outwardly over the rolls by centrifugal force, while culls, rough and imperfect specimens, pebbles and particles of dirt mixed in with them are frictionally engaged by the yielding rolls and drawn between them for discharge separately from the smooth perfect beans or grain which successfully traverses the roll to their outer ends.

My grain sorting machines are designed for sorting various kinds of grains that vary in size, consequently some provision must be made for adjusting the rolls of each pair relative to each other. In my present structure I provide simple, inexpensive, accessible and durable means for bodily shifting one group of rolls relative to an adjacent group, in contradistinction to individual roll adjustment, and in consequence of such roll adjusting means I can quickly change my machine for a desired sorting of grains, seeds and other matter that varies in size.

My invention will be hereinafter more fully described and then claimed, and reference will now be had to the drawings, wherein

Figure 1 is a plan of a portion of a sorting machine including my improvement;

Fig. 2 is a side elevation of the same;

Fig. 3 is a vertical sectional view of the greater part of the machine, taken on the line III—III of Fig. 1, and

Fig. 4 is an enlarged vertical sectional view taken on the line IV—IV of Fig. 1, showing one of the adjusting devices.

In order that my present invention may be readily understood, I have deemed it advisable to illustrate the greater part of a sorting machine, but have left off certain parts that are unnecessary for an understanding of my improvement. The machine shown in the drawings comprises a base 1 having a central socket or pedestal 2 for a tubular column 3 and mounted on the upper end of said column is a circular grain distributing plate or head 4 on which is deposited, from a feed hopper 5, the grain or

material to be sorted. Ordinarily there is sufficient vibration of the machine to cause the grain of the spiral or rib on the plate 4 to feed off at the peripheral edges of the distributing plate. In some instances there may be special provision to insure a peripheral distribution of grain from the plate 4.

Mounted on the column 3 is a bracket 6 having a bearing 7 for the inner end of a driven shaft 8, said shaft having its outer end journaled in an upstanding bearing 9 carried by the base 1. The shaft 8 may be driven by hand or any suitable power means.

Supported by the bracket 6 and rotatable about the column 3 is the hub portion 10 of a downwardly facing horizontal rack 11 constantly meshing with a beveled pinion 12 suitably fixed on the shaft 8 so that the rack 11 may be revolved about the vertical axis of the column 3. The rack 11 corresponds to a horizontally disposed beveled gear wheel forming part of a rotary circular carrier having an inner annular wall 13 and an outer annular wall 14 with said walls connected by radially disposed webs or ribs 15. These webs or ribs are inclined upwardly at a slight angle to the horizontal so that the outer annular wall 14 will be supported in a plane above the plane of the inner annular wall 13, and the upper edges of said walls are provided with sets of bearings 16, for the spindles 17 of rolls 18. The inner spindles 17 of said rolls are provided with gear wheels 19 and 20, the gear wheels 19 being at the outer sides of the bearings 16 of the wall 13 and the gear wheels 20 at the inner sides of said bearing the said gear wheels 20 meshing with a stationary upwardly facing rack or horizontal gear wheel 21 fixed on the column 3 above the hub portion 10 of the rotatable rack 11.

The rolls 18 by reason of the bearings 16 are disposed at an angle to the horizontal and are also radially disposed relative to the axis of the machine and equally spaced. The rolls may include rubber or other yielding material in their construction and constitute a group of radially disposed circumferentially revolved rolls that are driven about their axes by virtue of the stationary rack 21 and the gear wheels 20 when the group of rolls is bodily revolved by virtue of the rack 11 and the pinions 12.

The outer wall 14 of the roll carrier is provided with a plurality of sockets 22 and mounted in said sockets are posts 23 that

may be in the form of bolts. Rotatable about the posts 23 and bearing on the sockets 22 are exteriorly screwthreaded sleeves 24 having nut heads 25 to facilitate rotating said sleeves. In screwthreaded engagement with the sleeves 24 are the nut brackets 26 of a circular frame 27 and it is by virtue of the rotatable screw sleeves 25 that the frame 27 may be raised and lowered relative 10 to the outer wall 14 of the roll carrier. The frame 27 constitutes the outer wall of another roll carrier which includes an inner annular wall 28, a horizontally apertured wall 29, and an upstanding annular wall 30, said wall being connected to the wall or frame 27 by a plurality of radially disposed ribs or webs 31. The annular wall 30 is at the outer edge of the wall 29 and surrounds the distributing plate 20 40 in spaced relation thereto, so that the matter to be sorted may pass downwardly from the head 4 on to the wall 29 and through the apertures 32 thereof.

The frame or wall 27 and the inner annular wall 28 are provided with bearings 33 for the spindles 34 of rolls 35, similar to the rolls 18, and on the inner ends of the spindles 34, between the wall 28 and the inner ends of the rolls 35, are gear wheels 36 adapted to mesh with the gear wheels 19 of the lower roll carrier. It is through the medium of these meshing gear wheels that the rolls 35 of the upper carrier may be driven in synchronism with the rolls 19 of the lower carrier, the upper rolls revolving in a reverse direction to the lower rolls in order that matter to be sorted may feed between said rolls. By reference to Fig. 3 it will be noted that the horizontal wall 29 of the upper roll carrier is in proximity to the distributing plate 4, and forms an annular guard over the gear wheels of the pairs of rolls, preventing foreign matter from interfering with the operation of the meshing gear wheels or the rack 21 and the gear wheels or pinions 20.

Below the lower roll carrier is an inner hopper 37 supported from the column 3 and provided with a discharge pipe 38, said hopper receiving sorted matter from between the rolls of each pair. About the hopper 37 and suitably supported from the base 1 and the column 3 is an outer hopper 39 having a discharge pipe 40. This outer hopper is 50 55 adapted to receive sorted matter that is car-

ried outwardly by centrifugal action along the peripheries of the rolls, the sorted matter being discharged at the outer ends of the rolls to fall into the outer hopper 39.

In view of my former patents, it is believed that the operation and utility of the machine is apparent, but I desire to direct particular attention to the adjustment of the upper roll carrier relative to the lower roll carrier for the reason that the upper rolls may be easily and quickly shifted relative to the lower rolls to provide a desired pass between the rolls of each pair. It is in consequence of this adjustment that the passes may be regulated according to the matter to be sorted. In so much as the rolls may have different kinds of yieldable covers or surfaces and said rolls driven at a desired speed, it is obvious that the width of the passes between said rolls or the draw of said rolls will permit of a large variety of matter being sorted in my machine.

A preferred form of adjusting the upper roll carrier relative to the lower roll carrier has been shown, but it is to be understood that the adjusting devices may be varied or changed in construction without departing from the scope of the appended claims.

What I claim is:—

1. In a centrifugal sorting machine, a lower roll carrier, an upper roll carrier, a plurality of driven rolls in each carrier, the rolls of each carrier being disposed approximate to the rolls of the other carrier to form passes for sorting, and means for adjusting one carrier relative to the other.

2. A sorting machine as called for in claim 1, wherein the upper roll carrier is supported from the lower roll carrier by adjusting means between said carriers.

3. A centrifugal sorting machine comprising a rotatable lower roll carrier, rolls in said carrier adapted to be driven when said carrier is revolved, means for driving said carrier, an upper roll carrier, rolls in said upper carrier adapted to be driven from the rolls of the lower carrier, and means between said carriers for adjusting the upper carrier relative to the lower carrier.

4. A centrifugal sorting machine as called for in claim 3, wherein the last mentioned means supports the upper roll carrier relative to the lower roll carrier.

In testimony whereof I affix my signature.

RUSSELL V. JUDSON.
